UNITED STATES PATENT OFFICE

2,654,098

STAND AND BASSINET COMBINATION

Mary E. Heyward, Brockton, Mass., assignor to
American Hospital Supply Corporation, Evans-
ton, Ill., a corporation of Illinois

Application August 20, 1948, Serial No. 45,399

4 Claims. (Cl. 5-2)

1

This invention relates to a stand and bassinet combination.

It is common practice to equip a bassinet unit with wheels, a cabinet being supported upon the frame structure, and to move the entire unit about the hospital, etc. This type of structure is unsatisfactory in that the cabinet and the materials therein are all carried through the corridors and into the mother's room and are subjected to the possibility of contamination, etc. Further, such structures are unsatisfactory because they require the nurse to stoop over frequently in securing things from the cabinet, etc., and in the movement of the structure, both the cabinet and bassinet have to be moved together.

An object of the present invention is to provide a structure obviating the above disadvantages and providing a mobile bassinet structure readily separable from the stand or cabinet structure. Yet another object is to provide a combination in which a mobile cabinet structure may be interlocked with a stand which provides a table and cabinet, the stand serving to stabilize the bassinet and yet permitting these parts to be readily separated when it is desired to move the bassinet to a different room, etc. Yet another object is to provide a bassinet and stand combination in which the stand table is adapted to be received within the bassinet supporting frame while at the same time providing a cabinet at table height at one end of the table and adapted to be brought adjacent the bassinet when the parts are in telescoping position. Other specific objects and advantages will appear as the specification proceeds.

The invention is illustrated, in a single embodiment, by the accompanying drawing, in which—

Fig. 1 is a perspective view of a stand structure embodying my invention; Fig. 2, a perspective view of a bassinet structure adapted to be brought into cooperative relation with the stand shown in Fig. 1; Fig. 3, a vertical sectional view showing the bassinet structure and stand structure in telescoping relation; and Fig. 4, an enlarged detail sectional view showing mechanism for releasably locking a fence structure in elevated position.

In the illustration given, A designates a stand structure and B designates a bassinet structure.

The stand A may be of any suitable construction. In the illustration given, I provide a table 10 supported at one end by the legs 11 and at its forward end by the leg 12. Upon the rear end of the table is supported a cabinet 13 having a

2

partition floor 14 and doors 15. It will be understood that the cabinet may be of any suitable type or construction. I prefer to provide a frame 16 for receiving a card bearing the baby's name. If desired, one of the legs 11 may be provided with a basin supporting ring 17.

The table 10 may be provided with fences 18 as a protective measure when the baby is being bathed or dressed on the table. Any suitable fence structure which may be brought into the raised position illustrated and then moved into a position below the table or to one side of the top of the table, may be provided. By moving the fences away from the top of the table, the parts A and B may be brought into telescoping relation, as illustrated in Fig. 3. The fences may be swung downwardly into a position along the top of the table or they may be supported upon rotatable members, as illustrated in Figs. 1 and 4.

10 Here, the fences are each carried upon a shaft 19 rotatably supported in bosses on the table 10, and each shaft may be equipped with a locking member 20 adapted to engage a pivotally mounted latch 21 carried by the boss 22. A spring 23 normally urges each latch toward engagement with a tooth 24 of a member 20. It will be understood that any suitable fence structure mounted for movement away from the top of the table may be employed.

15 The bassinet structure B may also be of any suitable construction. The bassinet may be made a permanent part of the frame structure or it may be formed as a separable part and thus be carried by a frame structure equipped with wheels. In the specific illustration given, I provide a bassinet 25 formed of plastic material or of any other suitable material and the bassinet is supported upon a frame 26. In the specific illustration given, the frame 26 comprises a pair 20 of tubular side panels 27 connected at their tops by the cross-bars 28 and 29. A single cross-bar 30 at the lower end of the frame 26 may also be provided.

25 For suspending the bassinet 25 within the frame 26, I provide the depending arms 31 illustrated more clearly in Fig. 2. It will be understood that any number of arms may be provided so that the bassinet may be supported upon a horizontal plane, or, if desired, the bassinet may be tilted. I prefer, however, to support the bassinet 25 in a horizontal plane upon the frame 26.

30 The frame 26 is provided with wheel-equipped casters 32. It will be understood that wheels of any desired size facilitating the movement 35 of the bassinet may be provided.

3
Operation

In the operation of the structure, the bassinet combination will ordinarily be supported in the telescoped position with respect to stand A, as shown in Fig. 3. Here, the frame structure 26 normally supports the bassinet 25 above the table 10 and adjacent the cabinet 13. In this position, the stand A serves as a stabilizer or anchor for the mobile bassinet unit, holding it against lateral movement and the bassinet is maintained in a position close to the cabinet 13 in which the supplies are maintained. When it is desired to bathe the baby, the structure 26 may be moved away from the table and the baby transferred to the table 10, the fences 18 being swung to their elevated position, as shown in Fig. 1. After bathing, the baby is returned to the bassinet; the fences are swung down to lowermost position and the structure 26 is moved into the telescoping relationship with the table 10, as shown in Fig. 3.

When it is desired to take the baby to its mother's room, the structure 26 may be moved away from stand A and thus only the bassinet will be carried through the corridors and to the mother's room. Later, the structure 26 is returned and brought into the position shown in Fig. 3 where the mobile bassinet unit is thus anchored by the relatively rigid stand.

In all of the foregoing operations, it will be noted that the nurse is not required to stoop or bend to any substantial extent because all of the dressing and bathing operations are performed at table height and the cabinet is also within easy reach at the standing height of the nurse. At the same time, the cabinet is located also in horizontal alignment with the bassinet when it is brought into the position shown in Fig. 3.

The resulting structure is extremely compact, taking up no more space than has heretofore been required for a bassinet while, at the same time, permitting the movement of the bassinet away from the stand whenever desired.

While in the foregoing specification, I have set forth a specific structure in considerable detail for the purpose of illustrating an embodiment of the invention, it will be understood that

such details of structure may be varied widely by those skilled in the art without departing from the spirit of my invention.

I claim:

5. 1. In combination, a stand consisting of a table having two legs at one end and a centrally located leg at the other, a cabinet supported upon one end of the table, a wheel-equipped frame having sides spaced apart and removably receiving said table, and a bassinet supported by said frame at a position above said table.
10. 2. In combination, a stand consisting of a table having two legs at one end and a centrally located leg at the other, a cabinet supported upon one end of the table and providing compartments open at their ends, a wheel-equipped frame having sides spaced apart and removably straddling said table, and a bassinet supported by said frame at a position above said table.
15. 3. In combination, a stand consisting of a table having a plurality of legs providing a support therefore, a cabinet supported upon one end of said table and providing compartments, a wheel-equipped frame having sides spaced apart and removably receiving said table, and a bassinet supported by said frame at a position above said table.
20. 4. In combination, a stationary stand comprising a table having depending legs resting upon the floor and stabilizing the table against movement upon the floor, a cabinet supported at one end of the table and providing compartments therein, and a mobile bassinet-supporting frame comprising side wall members secured together in spaced relation and removably receiving said table, said frame being equipped with wheels, and a bassinet supported by said frame at a position above said table.

MARY E. HEYWARD
